JACOB MOSKOWITZ

Inventor:

By his attorney W. A. Seeler

UNITED STATES PATENT OFFICE.

JACOB MOSKOWITZ, OF BROOKLYN, NEW YORK.

BOOK-CORNER PROTECTOR.

Application filed August 5, 1927. Serial No. 210,759.

This invention relates to book corner protectors.

Among the objects of this invention is to provide a book corner protector made of two pieces of metal having beaded engagement with each other and yet having an edge wall of maximum thinness along the edge of the book corner.

A further object of this invention is to provide a book corner protector of two-piece construction having beaded edge engagement constituting a re-enforcement for said protector and an inward extending finger piece to facilitate removal of the protector from a book cover.

Still a further object of this invention is to provide an improved device of the character described wherein said inward extending bead creates the impression of increased thickness and solidity of said device, and provides particularly for neatness in edge formation of the device.

Still a further object of the invention is to provide a device having the advantages above enumerated and which is very inexpensive to manufacture.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view of a book provided with corner protectors embodying the invention.

Fig. 2 is a perspective outside view of said book corner protector in detached position.

Fig. 3 is a perspective inside view of the device shown in Fig. 2.

Fig. 4 is a sectional view taken on the line 4—4 of Fig. 3.

Referring in detail to the drawings, 10 denotes a book corner protector embodying the invention, and adapted to be secured upon the covers of any book 11.

Said book corner protector is made of two pieces 12 and 13, which are of any suit-

able material preferably polished nickel steel. The pieces 12 and 13 are of triangular form, the former constituting the outside member and having edge walls 12^a, and the latter constituting the inside member positioned within the walls 12^a. The walls 12^a have flanges 12^b making a comparatively sharp right angle therewith, and projecting inward to have beaded engagement with the member 13 as shown at B. The bead B forms a re-enforcement for the device 10 to prevent damage to same as for instance at 10^a, in the event a book is dropped. The walls 12^a, however, provide a single thickness of metal along the edges of the book, thus insuring minimum thinness of the device and preventing same from catching at the open ends 10^b thereof.

The beads B increase the thickness and solidity in appearance of the device 10, are flat in form, and permit a high degree of neatness in construction of said device. No solder, or the like, is used, so that the device 75 can be inexpensively manufactured.

To provide for reliable attachment of the device to a book cover, a plurality of indentations 13^a are provided in the member 13. Removability of the protector 10 is facilitated by the bead B which, for this purpose, acts as a finger piece.

To prevent the outer or exposed surface of the protector 10 from becoming scratched a design 10^c is provided on the member 12 and the walls 12^a thereof.

I claim:

1. In a book corner protector, the combination of an outside member, and an inside member, the former having edge walls 90 within which the inside member is positioned, said walls having inward extending flanges, said flanges having beaded engagement with the inside member.

2. In a book corner protector, the combination of an outside member, and a separate inside member, the outside member having edge walls extending toward the inside member, said inside member being positioned within said edge walls, said edge walls having beaded engagement with the inside member, the bead being inside of said edge walls.

In testimony whereof I affix my signature.

JACOB MOSKOWITZ.
